UNITED STATES PATENT OFFICE.

WASHINGTON H. CHAPMAN, OF DETROIT, MICHIGAN.

THERMOPRESSURE REGULATOR.

Application filed April 18, 1922. Serial No. 555,214.

To all whom it may concern:

Be it known that I, WASHINGTON H. CHAPMAN, a citizen of the United States, residing at Detroit, county of Wayne, State 5 of Michigan, have invented a certain new and useful Improvement in Thermopressure Regulators, and declare the following to be a full, clear, and exact description of the same, such as will enable others skilled in 10 the art to which it pertains to make and use the same, reference being had to the accompanying drawings, which form a part of this specification.

This invention relates to thermo-pressure 15 regulators and the object of the invention is to provide a device for controlling the difference in pressure between a boiler or a steam supply line and a return line. Another object of the invention is to provide a 20 thermo-pressure regulator comprising a thermostatic element which is operated by the temperature of the steam to control steam pressure. The principal and novel feature of this invention is embodied in the 25 mechanism for controlling steam pressure by temperature. A further object of the invention is to provide a device of the character described comprising a thermostatic or expansible closed member containing a 30 volatile fluid, the said member being expansible upon increase of temperature to reduce the steam pressure and upon decrease of temperature is contracted to increase the steam pressure. This device may be applied 35 either to a steam heating boiler to control the difference in pressure between steam line and atmosphere or between the steam and the return line or to a steam heating line to control the difference in pressure between 40 the live steam and return lines. These objects and the several novel features of the invention are hereinafter more fully described and claimed and the preferred form of construction by which these objects are 45 attained is shown in the accompanying drawings in which—

Fig. 1 is a side elevation of a steam boiler equipped with my improved thermo-pressure regulator.

Fig. 2 is an enlarged elevation of the thermo-pressure regulator.

Fig. 3 is a section taken on line 3—3 of Fig. 2.

Fig. 4 is a plan view showing the connection of the regulator between a steam pressure line and return line.

As shown in Fig. 1 the steam boiler is provided with a steam pressure line 1 and a return line 2. A line 3 of smaller diameter is connected into the pressure line 1 and at the opposite end opens into a chamber 4 shown in Fig. 3. This chamber 4 contains a closed thermostatic member 5 which is partially filled with a volatile fluid such as alcohol or ether. This member 5 is mounted 60 on a stud 6 at the bottom which prevents downward expansion of the member 5 and a short rod 7 extends upwardly from the member 5 through a packing nut 8 and is pivoted to an arm 9 above the chamber 4. 70 This thermostatic member 5 as will be readily understood from Fig. 2 is expansible and contractable upon change of temperature in a vertical direction only so that the rod 7 is moved up or down to produce a corresponding movement of the arm 9. The arm 9 is pivoted at 10 on a bracket 11 and the end of the arm 9 is connected by means of a rod 12 to the draught door 13 of a furnace, the expansion of the member 5 moving the rod 9 to close the door 13 and contraction of the member 5 moving the rod 9 to open the door 13 as will be readily understood. The chamber 4 is provided with an aperture 14 opening into a reservoir 15 80 which is adapted to fill with water or condensate from the return line 2. Mounted in the reservoir 15 is a tube 16 having a series of apertures in the lower end thereof open to the reservoir and this tube 16 opens into 85 a chamber 17 at the upper end. The chamber 17 is connected to the return line 2 by means of a conduit 18 and a bypass 19 is provided connecting the return line 2 with the reservoir 15. The reservoir 15, 90 chambers 4 and 17 and line 18 are normally filled with water or condensate to about the level shown in the line 2 in Fig. 3 and as the water is cooler than steam the member 5 is contracted thus opening the door 13 as 95 shown in Fig. 3. Due to the draught door 13 being open the fire in the furnace will burn with more intensity thus building up the steam pressure so that steam passes through the lines 1 and 3 and due to its pressure forces the water or condensate down in the chamber 4 and reservoir 15. By this 100 pressure water is forced through the apertures in the lower end of the tube 16 upwardly through the tube 16 and chamber 17 110 and through the line 18 into the return line 2 the water also partially filling the by-pass

19 due to the pressure of the steam. As the water in the chamber 4 is discharged through the aperture 14 the steam comes in contact with the member 5 or influences the 5 temperature thereof thus heating the volatile fluid therein and expanding the member 5 which moves the rod 7 upwardly and turns the arm 9 on the pivot 10 to close the draught door 13 by means of the rod 12. 10 When the draught door 13 is closed the fire in the furnace burns with less intensity so that as the steam pressure is reduced the pressure is decreased in the chamber 4 allowing the water to flow from the return line 2, through the line 18 into the chamber 17 and down through the tube 16 and through the apertures in the lower end thereof into the reservoir 15. As the water passes into the reservoir 15 it rises in the chamber 4 15 cooling the member 5 which contracts and by means of the rod 7, arm 9 and rod 12 the draught door is again opened. By setting the weight 20 on the arm 9 the device will operate to maintain a practically even 20 pressure in the steam line or a uniform difference in pressure between the steam line and the return line so that the fluctuation of water in the chamber 4 to produce contraction or expansion of the member 5 varies 25 but slightly, the device maintaining a greater pressure when the weight 20 is moved to the right of Fig. 2 and a lesser pressure when the weight is moved to the left as will be readily understood. 30 The by-pass 19 and reservoir 15 take the place of the usual steam loop between a steam and a return line and the by-pass 19 prevents the possibility of entirely emptying the reservoir of reserve water under 35 continued pressure. Should a high continuous pressure build up in the line 3 and chamber 4 the water will be discharged from the reservoir 15 as hereinbefore described until the level of water is below the opening of the by-pass 19 into the reservoir 40 15. At this time the steam may flow through the by-pass 19 into the return line 2 thence through the line 18 into the chamber 17 and upper end of the tube 16, the 45 pressure of the steam in the tube 16 and chamber 17 preventing upward flow of water through the said tube normally caused by the pressure on the body of water in the reservoir. The steam may then back 50 up in the return line 2 until the pressure decreases due to the draught door 13 being closed by expansion of the member 5. As the pressure again reduces to normal the 55 operation of the device continues as before. 60 It will be noted however that flow of steam through the by-pass can only occur under continued high steam pressure and in the average installation such pressures never occur unless the draught door is held open 65 against the action of the device. The reser-

voir is provided with a series of apertures 90 in vertically spaced relation permitting the length of the by-pass 19 to be varied whereby this device is adapted to be connected up for use with steam boilers having different distances between the water level of the boiler and the level of the return line. In all instances the point of connection of the lower end of the by-pass with the reservoir should be above the water level 70 75 of the boiler.

In Fig. 4 I have shown an alternative form of the device for controlling the difference in pressure between a steam supply line 21 and a return line 22. The supply line 21 is provided with a valve 23 and the line 3 is connected into the steam line 21 beyond the valve 23 and the opposite end of the line 3 is connected into the chamber 4 as shown in Fig. 2. In this case the rod 12 is dispensed with and a short rod 24 extends upwardly from the apertured end 25 of the arm 9 and is connected to a lever 26 for operating the valve. The return line 22 is connected to the device in identically the same manner as the return line 2 shown in Fig. 2.

The operation of this device is the same as that shown in Fig. 3 and when the member 5 contracts the rod 9 is drawn down on the pivot 10 by means of the arm 7 thus raising the outer end 25 of the arm to cause upward movement of the rod 24 which moves the lever 26 to open the valve 23. As the valve 23 is opened the steam passes therethrough under pressure and through the line 21 and line 3 and the steam on coming in contact with the member 5 expands the said member causing the rod 7 to raise the arm 9 to depress the end 25 thereof thus moving the rod 24 and lever 26 downwardly to close the valve 23. By adjusting the weight 20 an almost constant pressure can be maintained in the line 21 beyond the valve 23 corresponding to the position of the weight 20 on the rod 9. With the arrangement shown in Fig. 4 the device may be utilized to control the difference in pressure between the steam line and the return line where the steam is supplied to heat a 100 building by a central heating station.

From the foregoing description it becomes evident that the device is very simple and efficient in operation, will automatically control the difference in temperature 105 between a steam and return line and provides a device which accomplishes the objects described.

Having thus fully described my invention, its utility and mode of operation, what 110 I claim and desire to secure by Letters Patent of the United States is—

1. A thermo-pressure regulator for controlling the difference in pressure between a 115 live steam line and a return line comprising 120

a chamber open to the steam line, a reservoir adapted to contain water or condensate from the return line open to the chamber, a second chamber, a tube opening into the 5 second chamber and extending downwardly into the reservoir, the tube being open to the reservoir at the lower end, a conduit connecting the said second chamber with the return line, a by-pass connected at one end 10 to the return line and opening at the other end into the reservoir above the open end of the said tube, a closed member in the first chamber containing a volatile fluid, the said member being expansible or contractable 15 upon change of temperature, a control lever pivotally supported relative to the first chamber, means for operating the control lever by expansion or contraction of the expansible member and a pressure control 20 means with which the control lever is connected.

2. A thermo-pressure regulator for controlling the difference in pressure between a live steam line and a return line comprising 25 a chamber open to the steam line and adapted to contain steam or condensate, a closed member in the said chamber containing a volatile fluid, the said member being expansible or contractable under change of 30 temperature, a reservoir open to the chamber and adapted to contain steam or condensate, a tube in communication with the return line extending downwardly within and open to the reservoir at the lower end, a by- 35 pass connecting the reservoir with the return line, and a pressure control device adapted upon contraction of the said closed member to effect an increase in pressure in the steam line and upon expansion of the 40 said member to effect a decrease in pressure in the steam line.

3. A thermo-pressure regulator for controlling the difference in pressure between a live steam line and a return line comprising 45 a chamber open to the steam line, a closed member therein containing a volatile fluid, the said member being expansible or contractable under change of temperature, a reservoir beneath the chamber and open thereto, a tube in communication with the return line at one end and opening within the reservoir at the opposite end, a by-pass 50 connecting the reservoir with the return line, and means operated by expansion or contraction of the expansible member to effect variation of pressure in the steam line.

4. A thermo-pressure regulator for controlling the difference of pressure between a live steam line and a return line comprising 55 a chamber open to the steam line, a thermostatic element therein adapted to expand or contract upon change of temperature, a reservoir beneath the chamber and open thereto, a tube in communication with the 60 return line extending downwardly into the

reservoir and provided with apertures in the lower end thereof, a by-pass opening at one end intermediate the ends of the reservoir and opening at the opposite end into the return line, a control lever operated by expansion or contraction of the thermostatic element, and a pressure control device with 70 which the control lever is connected.

5. A thermo-pressure regulator for controlling the difference of pressure between a 75 live steam line and a return line comprising a chamber open to the steam line, a member therein expansible or contractable under change of temperature, a reservoir beneath the chamber and open thereto, a by-pass connecting the return line with the reservoir, and means operable by the expansible member to effect variation of steam pressure.

6. A thermo-pressure regulator for controlling the difference in pressure between a 85 live steam line and a return line comprising a chamber connected between the steam and return lines including a seal to normally prevent flow of steam into the return line, a closed member containing a volatile fluid 90 subject to the variation of temperature within the chamber, the said member being expansible or contractable upon change of temperature, and means operable by the expansible member to effect variation of pressure 95 in the steam line.

7. A thermo-pressure regulator for controlling the difference in pressure between a live steam line and a return line comprising 100 a chamber open to the steam line, a thermostatic element adapted to expand or contract upon change of temperature in the said chamber, a reservoir beneath the chamber and open thereto, a tube in communication with the return line extending downwardly 105 into the reservoir and provided with apertures in the lower end thereof, a by-pass opening at one end intermediate the ends of the reservoir and opening at the opposite end into the return line and means operated by expansion or contraction of the thermostatic element to effect variation of pressure 110 in the steam line.

8. A thermo-pressure regulator for controlling the difference in pressure between a live steam line and a return line comprising 115 a chamber connected between the steam and return line including a seal to normally prevent flow of steam into the return line, a closed member in the said chamber containing a volatile fluid, the said member being expansible or contractable under change of temperature, and means operable by the expansible member to effect variation of pressure 120 in the steam line.

9. A thermo-pressure regulator for controlling the difference in pressure between a live steam line and a return line comprising 125 a chamber open to the steam line, a closed expansible and contractable member therein 130

- containing a volatile fluid, a reservoir beneath and open to the said chamber, a tube in communication with the return line and opening within the reservoir at the opposite end, a by-pass opening to the return line at a point above the water level therein at one end and with the reservoir at the opposite end, the said reservoir being provided with means whereby the point of connection of the by-pass may be altered in a vertical plane, and means operated by expansion or contraction of the said member to effect variation in pressure of the steam line.
10. A thermo-pressure regulator for controlling the difference of pressure between a steam line and a return line, comprising a chamber open to the steam line, a member therein contractable or expandable under change of temperature, a reservoir beneath

the chamber and open thereto, a passageway 25 leading from near the bottom of the reservoir to the return line beneath the water level thereof, a by-pass connected at one end with the return line above the water level thereof and with the reservoir, said reservoir being adapted for connection therewith of the opposite end of the by-pass at a series of points in vertically spaced relation permitting use of a by-pass of a length to correspond with the distance between the return line and water level of a boiler of any particular installation, and means operable by the expandable member to effect variation in steam pressure.

In testimony whereof I sign this specification.

WASHINGTON H. CHAPMAN.
